UNITED STATES PATENT OFFICE.

JOHN T. SHEA, OF CRESTON, IOWA.

JEWEL-PIN SETTER.

Application filed February 17, 1921. Serial No. 445,866.

To all whom it may concern:

Be it known that I, JOHN T. SHEA, a citizen of the United States, residing at Creston, in the county of Union and State of 5 Iowa, have invented new and useful Improvements in Jewel-Pin Setters, of which the following is a specification.

My present invention relates to tools for watchmakers or watch repairers and more 10 particularly to tools for use in the setting of jewel pins in the roller table or balance of a watch. The primary objects of the invention are to provide an improved tool or implement of this character which is simple 15 in construction, may be handled with facility, and which enables the jewel pin to be set in the roller table or balance of a watch without the necessity of removing the balance from the bridge or detaching the 20 hair spring or roller table from the balance, thus saving much time and labor in the setting of jewel pins.

To these and other ends, the invention consists in certain improvements, and combinations and arrangements of parts, all as will be hereinafter more fully described, the novel features being pointed out particularly in the claims at the end of the specification.

30 In the accompanying drawing:

Figure 1 is a perspective view of a jewel pin setter constructed in accordance with the present invention, it showing the bridge, balance, hair spring and related parts in 35 the relative positions they occupy in setting the jewel pin in the roller table.

Figure 2 is a top plan view of the tool, and

Figure 3 is a side elevation of the tool.

40 Similar parts are designated by the same reference characters in the several views.

A simple and efficient form of the invention is shown in the accompanying drawing and will be hereinafter described in detail, but it is to be understood that the invention is not restricted to the particular construction shown, as equivalents thereof within the scope of the claims hereto annexed are contemplated.

50 In the present instance, the tool or implement comprises a suitable base or support 1, that shown being flat in order that it may rest upon a table or work-bench and will support and position the bridge or cock 55 2 upon the upper surface thereof. The bridge contains a jewel bearing for one end

of the balance staff 3 and it also has one end of the hair spring 4 attached thereto, as usual. In order to hold the bridge down and in proper position on the base, 60 a clip or equivalent holding device is provided, a spring clip 5 being preferably used beneath which the bridge may be inserted edgewise, the clip pressing the bridge down upon the top surface of the base and 65 retaining it in such position until it is desired to remove the same.

According to the present invention, the jewel pin may be set in the roller table without the necessity of removing the roller 70 table or the hair spring from the balance or detaching the balance from the bridge. This is accomplished by supporting the balance in an axially displaced or dissociated relation to the bridge while the hair spring 75 remains attached to the bridge and the balance, in consequence of which the hair spring is drawn away from the balance and hence is not affected by the heat to which the roller table is subjected in the setting of 80 the jewel pin. In the construction shown, the balance is supported with the parts associated therewith, in the relative positions described, by a clamp which comprises a pair of members 6 and 7, one or both composed preferably of copper or other good heat-conducting material, one of these members, the member 6 in the present instance, being fixed to or formed as a part of a standard or upright 8 which latter is fixed 90 to the base 1, and the other member 7 being pivoted at 9. The ends 10 and 11 of the clamp are flat and adapted to engage the opposite flat faces of the roller table 12 at one side of the balance staff, leaving the 95 jewel pin 13 or its receiving socket readily accessible to the operator. Preferably, a spring 14 acts on the clamp members 6 and 7 to maintain them in engagement with the roller table, thus leaving both hands of the 100 operator unhampered in the setting of the jewel pin. The ends 15 and 16 serve as finger pieces to be pressed together and separate the gripping ends of the clamp for the purpose of inserting or removing 105 a balance.

The clamp for the roller table occupies such a position relatively to the base or support which holds the bridge that, when the roller table of a balance is engaged by 110 the clamp, the balance will be displaced axially relatively to the bridge, the adjacent

end of the balance staff being withdrawn from its bearing in the bridge, and the hair spring being drawn out axially and away from the balance, the hair spring remaining attached to the balance and bridge and being withdrawn from the influence of the heat to which the roller table is usually subjected in order to heat and soften the shellac or other cement employed in securing the jewel pin in its socket in the roller table. One of the clamp members, the member 6 in the present instance, is provided with a laterally projecting enlarged portion to receive heat from a lamp or other heating device and supply such heat to the roller table.

The present invention enables jewel pins to be set easily and with facility and it saves the time and labor heretofore expended in detaching, replacing and readjusting the hair spring, or removing and replacing the roller table, and it avoids distortion of the hair spring, either from the effects of heat, or from handling the parts.

I claim as my invention:—

1. A jewel pin setter comprising a base, means to hold the bridge in position thereon, and means secured to the base and occupying a fixed position above it to engage the roller table and to hold the balance in axially displaced relation with the bridge, said means being adapted to apply heat to the roller table.
2. A jewel pin setter comprising a base having means to hold the bridge in position thereon, and means for supporting the balance above and in dissociated relation with the bridge, comprising a member connected to the base and occupying a fixed position above it to engage one side of the roller table and a cooperative member arranged to engage the opposite side of the roller table, one of said members consti-

tuting heat applying means for the roller table.

3. A jewel pin setter comprising a base having means to hold the bridge in position thereon, and means mounted in fixed position on said base and having an overhanging portion above the base for holding the balance in dissociated relation with the bridge, while the hair spring connecting the bridge and balance is drawn away from the latter.

4. A jewel pin setter comprising a base provided with a bridge holding member, and a clamp rigidly mounted in relatively fixed position on the base to overlie a bridge thereon and operative to engage the roller table and hold the balance in axially displaced relation with the bridge.

5. A jewel pin setter comprising a base having bridge holding means thereon, and a clamp embodying cooperative members, one of which is rigidly mounted in relatively fixed position on said base, said members being adapted to engage the opposite faces of the roller table and thus support the balance in an axially displaced position above the bridge and with the hair spring connecting the bridge and balance drawn axially away from the latter.

6. A jewel pin setter comprising bridge-holding means, and a clamp embodying members to engage the opposite faces of the roller table to support the balance in axially displaced relation to the bridge, one of the members of the clamp having a laterally projecting heat-receiving portion.

In testimony whereof I have hereunto set my hand in presence of two subscribing witnesses.

JOHN T. SHEA.
